UNITED STATES PATENT OFFICE.

JOHN ZIMMERMAN, OF CHICAGO, ILLINOIS, ASSIGNOR OF ONE-HALF TO HARRY IRWIN
CROMER, OF CHICAGO, ILLINOIS.

REMOVABLE COVER FOR BOXES OR CANS.

No. 885,682.

Specification of Letters Patent. Patented April 21, 1908.

Application filed January 28, 1907. Serial No. 354,422.

To all whom it may concern:

Be it known that I, JOHN ZIMMERMAN, a citizen of the United States, residing in Chicago, in the county of Cook and State of Illinois, have invented certain new and useful Improvements in Removable Covers for Boxes or Cans, of which the following is a specification.

This invention relates to that class of removable covers having a depending rim or flange adapted to encircle and tightly close a circular box or can body, and provided with means for enabling the cover to be loosened or detached by expanding the lower portion of the flange or rim.

The principal object of the invention is to provide a simple, economical and efficient removable cover for boxes or cans.

A further object of the invention is to provide a removable cover having a circular or cylindrical depending flange or rim portion adapted to entirely encircle and render air tight a circular box or can body, and to provide such cover with suitable preferably integral means for enabling the lower portion of the flange to be expanded for the purpose of loosening the cover and enabling it to be readily removed in an efficient manner.

A further object is to provide a removable cover having a circular or cylindrical flange portion adapted to tightly close a circular box or can body, with means preferably integral with the cover, for enabling the cover to be detached or loosened by expanding the lower portion of the cover flange or rim, and in such a manner that the bead upon the box or can body is not required to perform any function in the operation of removing or loosening the cover and therefore may be made as small as desired, or dispensed with when desired, without affecting the efficiency in operation of the means for detaching or loosening the cover.

A further object is to provide a cover of the class described with means for enabling it to be loosened or detached in an efficient manner without the use of a plier, lever or similar tool, and in such a manner as to disturb the contents of the receptacle as little as possible and leave the bottom of the flange or rim somewhat expanded after the first removal so that the cover may be readily replaced and removed repeatedly.

Other and further objects of the invention will appear from an examination of the draw-

ings and the following description and claims.

The invention consists in the features, combinations and details of construction hereinafter described and claimed.

In the accompanying drawings Figure 1 is a plan view of a box or can provided with a cover constructed in accordance with my improvements; Fig. 2, a view of the cover in side elevation; Fig. 3 a side elevation of the box and cover shown in Fig. 1; Fig. 4, a central sectional elevation taken on line 4 of Fig. 1, looking in the direction of the arrow; Fig. 5, a sectional plan view taken on line 5, of Fig. 3, looking in the direction of the arrow; and Fig. 6, a bottom plan view of the cover showing the flange or rim in normal position in full lines, and showing the flaring or downwardly and outwardly inclined portions or lips depressed and the lower portion of the flange expanded, in dotted lines.

In constructing a box or can provided with a removable cover made in accordance with my improvements I provide a box or can body *a* formed preferably of sheet metal and which may be of any ordinary and well known form. The box here shown is of the form commonly used for containing shoe polish, stove polish, paste or similar material, and which, in order to properly protect the contents, is generally required to be air-tight. The box or can body is provided with a bead *b* for limiting the downward movement of the cover and increasing the tightness of the fit. For this purpose it is desirable that the upper side of the bead should be tapered inward gradually so as not to form an abrupt angle or shoulder. It therefore, becomes very desirable to provide a cover with means for enabling it to be readily loosened and removed independently of the bead or in the absence of a bead, and without requiring the presence or coöperation of a shoulder of any sort upon the box or can body. A cover *c*, formed preferably of sheet metal, is therefore provided, having an integral depending flange or rim *d* which is circular and preferably cylindrical at all points of normal engagement with the box or can body. In other words, the upper portion of the flange from a point above the upper edge of the can or box body to a point below such upper edge of the box or can is circular and preferably cylindrical. This circular portion of the flange is thus adapted to entirely en-

circle and tightly close a circular box or can body. This depending flange or rim portion of the cover is also provided with preferably a plurality of integral downwardly and outwardly inclined flaring portions or lips *e* which extend outward laterally beyond the circular or cylindrical portions of the flange and preferably on opposite sides of the cover so as to form inner concave faces *f* which extend outward laterally beyond the circular flange portions and the lower and most widely flaring portions of which lips are integrally connected with the lower edge of the flange where it is in binding engagement with the cylindrical walls of the box-body. A space is thus formed between the inner concave surface portions of these flaring portions or lips and the adjacent outer surface of the box-body. This construction of the downwardly flaring portions or lips enables them to be bent inward from normal position toward the box body thereby spreading the lower portions of the lips and expanding the lower portion of the flange so as to loosen or detach the cover. Substantially the entire portion of the depending flange *d* above the flaring portions or lips *e* is cylindrical. The lower portions of the flange which are between the flaring portions or lips are also cylindrical and in binding engagement with the box-body on opposite sides of the box and cover and on opposite sides of or between the flaring portions or lips, when in normal position. It will thus be seen that while the cover is adapted to tightly close a circular box or can body, the depression or inward bending of the outwardly and downwardly extending inclined portions or flaring lips will cause the lower portion of the flange *d* to expand, as indicated in dotted lines in Fig. 6. This may be readily accomplished by pressing inward upon or tapping one or both of the flaring or lip portions. By continuing the pressure or tapping—the latter being more effective—until the flaring portion of the flange is somewhat flattened, the normally cylindrical portions of the flange between the flaring portions or lips, or on opposite sides of such lips, will be expanded sufficiently without injury to the contents of the receptacle and without the use of a plier, lever or other similar element. In effect the diameter of the lower portion of the flange is increased so that the cover may be readily and repeatedly removed and replaced.

I prefer to have the lower edges of the flaring portions or lips extend outward in the form of the arc of a circle and flush with or below the level of the bottom edge of the flange of which they form a part—in other words, flush with or below the upper edge of the bead. The flaring portions or lips should also be, preferably, on opposite sides of the cover. By resting one against a support and tapping the other they thus coöperate in

expanding the flange and loosening or detaching the cover—the effect being thus practically doubled by the expenditure of the same degree of effort. The bottom portion and edge of the flange, when constructed as above described is elliptical, and in binding engagement with the cylindrical walls of the box-body at the shorter diameter of the elliptical portion of the flange, said flange extending outward laterally from the box-body on opposite sides of the box and cover at the longer diameter of the elliptical portion. It is not always necessary to bend the flaring portions of the flange inward to such an extent that they will not spring back to normal or initial position. The elliptical form of the lower portion of the cover-flange enables it to clamp or bind the walls of the box-body where the cylindrical portions of the flange between the laterally projecting portions or lips engage the box, in such a manner that the inward bending or flexing of the laterally projecting portions will loosen the cover and the flexibility due to the material used and the elliptical form of the lower portion of the flange will permit it to spring back to normal position. When the cover is made of sufficiently light sheet metal it is sometimes unnecessary to even employ an instrument of any kind, the pressure of the fingers being sufficient to spread or loosen the flange.

I claim:

1. A box-body, and a cover having a depending flange the upper portion of which is in engagement with the box-body and the lower portion of which is provided with box-engaging segmental circular portions in securing engagement with the box-body and with a laterally projecting flexible portion extending outward between such lower box-engaging portions of the flange and adapted to be bent inward and thereby spread the lower portion of the flange to loosen the cover, the portion of the box which is encircled by the cover flange being smooth and free from projection.

2. A box-body having annular side walls provided with an upper outer surface portion which is smooth and free from lateral projection, and a cover having a depending flange the upper portion of which encircles the smooth upper portion of the box-body and the lower portion of which is provided with box-engaging portions in securing engagement with the box-body and with laterally projecting flexible portions on opposite sides of the cover, between box-engaging portions of the flange, adapted to be bent inward and thereby spread the box-engaging lower portions of the flange, to loosen the cover.

3. A box-body having circular walls and having a bead near the top of the body and a marginal portion between the said bead and the upper edge of the body which is

smooth and free from projections and a cover having a depending flange the upper portion of which is circular and in engagement with the box-body and the lower portion of which is provided with box-engaging segmental circular portions on opposite sides of the box-body, and downwardly and outwardly inclined laterally projecting flexible portions on opposite sides of the cover, between box-engaging portions of the flange, adapted to be bent inward and thereby spread the box-engaging lower portions of the flange, to loosen the cover.

4. A box-body, and a metallic cover having a depending inclosing flange the upper portion of which is circular and in engagement with the box-body and the lower portion of which is elliptical and in binding engagement with the box-body at the shorter diameter of the elliptical portion of the flange, the elliptical portion of the flange, at its longer diameter, extending laterally beyond and out of engagement with the box-body on opposite sides of the cover and forming flexible flaring portions between box-engaging flange portions and adapted to be bent inward and thereby spread the lower box-engaging portion of the flange to loosen the cover.

JOHN ZIMMERMAN.
